UNITED STATES PATENT OFFICE.

JOHN R. CUMMINGS, OF CHICAGO, ILLINOIS, ASSIGNOR TO THE AMERICAN PRESS ASSOCIATION, OF SAME PLACE.

CLAMPING-TOOL.

SPECIFICATION forming part of Letters Patent No. 337,743, dated March 9, 1886.

Application filed March 18, 1885. Serial No. 159,368. (Model.)

To all whom it may concern:

Be it known that I, JOHN R. CUMMINGS, a citizen of the United States, residing at Chicago, in the county of Cook and State of Illinois, have invented certain new and useful Improvements in Clamping-Tools; and I do hereby declare the following to be a full, clear, and exact description of the invention, such as will enable others skilled in the art to 5c which it appertains to make and use the same.

My invention relates to an edging and clamping tool; and it consists of a tool for bending the edges of a thin sheet of metal over a suitable base or block, and at the same time 15 turning and clamping the edges of the metal so bent into suitable grooves or recesses formed in the base or block. It is especially designed for fastening an electro-shell plate upon a base 20 grooved or slotted to receive the edges of such a plate, and in this connection the invention will be described and illustrated.

In the accompanying drawings, Figure 1 is a front perspective view of my invention; Fig. 2, a side view in elevation; Fig. 3, a central 25 vertical section on line $x-x$ of Fig. 2; and Fig. 4, an end view of a base and shell, showing the manner in which the edges of the shell are bent and forced into the grooves of a base or block. Fig. 5 is a view of an electrotype-30 shell having flanges, to the bending and clamping of which my improvement is particularly adapted. Fig. 6 is a sectional detail view of 35 a portion of the tool, and Fig. 7 a detail.

In the drawings, A is the base of the tool; 35 B, an upright central post; C, a telescopic handle and plunger sliding on said post, and D a coiled spring placed within the handle C, resting upon the post B, and confined in place by the top e of handle C. Hinged to the handle on its opposite sides are arms d d, which carry the bending and clamping plates E E. Connected to these arms by a knee or other joint, f, are plates g.

E E are the bending or clamping plates, riveted to the plates g. The base A has a smooth under face, and on its sides is provided with flanges G, slotted to receive the bending-plates E, the flanges having their outer corners and surfaces rounded and inner face inclined toward 5c the base. Each slot is divided by a partition,

h, rounded to correspond to the rounded corners of flanges G, as shown. Through these slots pass the bending-plates E, each plate being provided with a central slot, i, to inclose the partitions h. The rounded upper surfaces 55 of partitions h and of the corners of the flanges G form bearings upon which the central portion, g', and the shoulders g² of the plates g ride when the clamping-plates are pressed down, as hereinafter described. The bending-60 plates extend below the base, and are provided with bevelled edges l.

In applying this tool to an electrotype-shell provided with plain flanges, as shown in Fig. 5, the shell is placed upon a block having 65 grooves m running adjacent to and running parallel with the upper face of the block. The plain even face of base A is placed over the lettered part of the shell, and when force is applied to the plunger C the base is pressed upon 70 the lettered face of the shell, leveling the under surface of the shell with the base-block, and at the same time the lower edges, l, of the bending-plates E are forced toward the block and into its respective grooves, drawing the 75 flanges of the shell tightly against the beads of the block, setting its flanges into the grooves against the lower sides of the beads, and fastening the shell securely thereto. The flanges are thus not only turned smoothly and 80 securely within the grooves, but the shell is stretched tightly across the base-block, and any buckling or bowing-up of the shell is prevented, and all irregularities of the shell smoothed out. The pressure upon the plunger 85 C being relieved the force of the spring automatically lifts the bending-plates, the tool is moved along the block without lifting it off, and the operation of bending repeated. Thus by a rapid succession of strokes upon the 90 plunger by the hand as the tool is moved along a column of any length of shell is securely clamped upon the base in a few seconds.

When the matter electrotyped on the shell is in the form for printing arranged in columns, the tool can be placed over the column for clamping on the shell with only a slight separation of the columns of the form, thus obviating the annoyance of taking the furniture out of the form and spreading the columns 100

apart, or of taking the base-block from the form, as would be required were the bending of the flanges done from the side.

This tool will be found useful in connection with a grooved base whenever it is desired for any purpose to turn the edges of a sheet of metal inwardly.

Having thus described my invention, what I claim is—

10 1. A tool for bending the edges of a metal plate, consisting in the combination, with the slotted base-plate and central post, of the handle or plunger sliding on said post, a spring, and the bending-plates and connecting-arms hinged to the plunger, substantially as and for the purpose described.

15 2. In a tool for bending the edges of a metal plate, the plunger, in combination with bend-

ing-plates, their supporting-plates, and connecting-arms hinged thereto, substantially as 20 and for the purpose set forth.

3. The combination of the base-plate provided with the slotted, rounded, and inclined flanges G and central partition, the bending-plates slotted to fit over said partitions, the 25 hinged connecting-arms, the sliding automatic plunger, to which said plates and arms are secured, the coiled spring, and the central post, substantially as described.

In testimony whereof I affix my signature in 30 presence of two witnesses.

JOHN R. CUMMINGS.
